COMBINED ILLUMINABLE MAKEUP MIRROR AND VANITY CASE

Douglas G. Long, Lombard, and Robert S. Waters, Oak-brook, Ill., assignors to Sunbeam Corporation Chicago, Ill.

Filed July 9, 1970, Ser. No. 23,877

Term of patent 14 years

Int. Cl. D6—07

U.S. Cl. D86—10

FIG. 1 is a perspective view of a combined illuminable makeup mirror and vanity case embodying our new design; FIG. 2 is an enlarged side elevational view thereof; FIG. 3 is a top plan view thereof; and FIG. 4 is a sectional view taken on line 4—4 of FIG. 3 thereof.

The design in closed position is plain and unornamented having a contour as indicated by FIGS. 2, 3 and 4.

We claim:

The ornamental design for a combined illuminable makeup mirror and vanity case, as shown and described.
